BUILDING CONSTRUCTION

Orley B. Lane, Washington, D. C.

Application June 5, 1936, Serial No. 83,686

10 Claims. (Cl. 72—16)

(Granted under the act of March 3, 1883, as
amended April 30, 1928; 370 O. G. 757)

The invention described may be manufactured and used by or for the Government for governmental purposes without the payment to me of any royalty thereon.

5 This invention relates in general to building construction and more particularly to a novel supporting and spacing means between the inner and outer wall structures of a building.

10 Heretofore the efforts to provide wall structures that will eliminate or resist the transmission of moisture, heat, sound and other vibrations through the walls have resulted in complex, expensive, and unwieldy construction not susceptible of re-use or interchanging.

15 It is therefore an object of this invention to provide a spacing, supporting and strengthening element for walls or other building structures that will comprise easily formed, easily removable interchangeable units necessitating the minimum of material and yet have the required strength for use in connection with wall or other structures or for use as a building structure itself.

20 Another object is to provide such a spacing and supporting element that when interposed between two wall structures will have the minimum surface contact therewith necessary for support so as to lengthen the solid path of travel from one wall to the other in order to minimize and resist the transfer of moisture, heat, sound 25 or other vibrations.

25 To these and other ends a simple removable form or the like may be used for casting an inner wall member having an elongated body portion with spaced staggered integral ribs extending alternately from the opposite sides of the body portion. The inner wall members also 30 may be precast or formed with their ends having complementary tongue and groove or like expedients for removable assembly and interchangeability. The solid path for transfer of moisture or sound from one face of the wall to that of the other consists solely of the body portion and ribs of the inner wall. Due to the staggering and spacing of the ribs, this solid 35 path is effectively greatly lengthened as compared to the actual distance between the faces of the wall. The longer the path is the greater the resistance to transfer of moisture and sound 40 is from one face of the wall to the other.

45 50 With the foregoing and other objects in view, the invention resides in the combination of parts and in the details of construction hereinafter set forth in the following specification and appended claims, certain embodiments being illustrated in 55 the accompanying drawing, in which:

Figure 1 is a view in longitudinal section through the mould showing the frame and moulded inner wall member cast therein.

Figure 2 is a view in longitudinal section through several inner wall members showing one 5 form of coupling means.

Figure 3 is a similar view showing another form of coupling means.

Figure 4 is a view similar to Fig. 3 showing another form of coupling means. 10

Figure 5 is an isometric view in section and in detail of a wall corner with the inner wall installed.

Figure 6 is a view in longitudinal section through a wall structure including an outer 15 stucco finish and an inner lath and plaster finish with the inner wall therebetween.

Referring more particularly to the drawing, Figure 1 shows one type of casting form with two side members 1 and 2 held spaced apart by tie 20 rods 3. The casting form may, as shown, include staggered sets of spaced boards 4 and 5 engaged by staggered sets of spaced wooden blocks 6 and 7, the latter being recessed at 8 to receive the boards. The blocks are also recessed 25 at 9 to receive wooden strips 10 and 11.

30 Into the trough thus provided are arranged longitudinal reinforcing members 12 and transverse reinforcing members 13. The concrete may then be poured into the trough and cast into the 35 shape determined by the inner dimensions of the trough or form.

As shown in Figure 1 the resulting shape of the inner wall member thus cast is a relatively thin elongated body portion 14 with a set of 35 narrow spaced ribs 15 on one side and a set of narrow spaced ribs 16 on the other side in staggered relation to the ribs 15, so that ribs 15 are spaced longitudinally from each other and from the longitudinally spaced ribs 16. 40

Referring now to Figures 2, 3 and 4, for sake of simplicity and ease in using the inner wall construction, the inner wall may be cast before erection into units which are relatively short longitudinally with their adjoining ends cast with 45 tongue and groove or other locking expedients, such expedients being shown at 17 in Figure 2, 18 in Figure 3 and 19 in Figure 4. It is practical to mould these units so that they extend a full story height. Thus, the only joints between 50 floors would be vertical and would be separated from the outer and inner wall facings by air spaces so as to prevent moisture penetration.

Referring now to Figure 6, which represents a 55 wall construction, the outer wall 20 may be stucco

and the inner facing 21 of plaster, covering laths which are not shown. As shown, the inner wall body portion 14 is spaced from the stucco on the outer side and the plaster on the inner side respectively by spaces 22 and 23 each of which is preferably at least as wide as the body portion 14, while the plaster rests on the vertical ribs 16 and the stucco on the vertical ribs 15. The seeping of moisture in from the stucco finish in order to reach the plaster must occur along the solid path provided for between the walls. In the present illustrated construction the most direct solid path from one wall to the other is doubled in length over the actual distance between the stucco and the plaster. It is contemplated that in actual construction this path may be lengthened to an even greater proportional extent and still retain the requisite strength and rigidity of wall construction. The greater the length of the solid path the greater opportunity is afforded for preventing the conduction of moisture and dissipation thereof before it reaches the plaster. The same is true of dissipation of heat, noises and other vibrations to which either of the two faces of the walls may be subjected.

As to Figure 6, the spaces 22 and 23 may be mere air spaces and found to suffice, or they may be filled with some suitable sound absorbing or heat insulating material represented at 24. Also the stucco may rest directly on ribs 15 and the plaster on the ribs 16. These ribs 16 may be so spaced as to form a continuation of ribs on a floor slab when the device is used in floor construction. In order to further safeguard against seepage of moisture, either or both of the sets of ribs may have affixed to their faces a moisture repellent substance 25. Also, as a further refinement, either or both of the sets of ribs may have affixed to the faces thereof or anchored thereto a suitable wooden nailing strip 26.

Figure 5 shows a corner section of a wall structure in which the inner facing comprises plaster 21 over laths 27 and the outer wall 28 of brick or the like. The showing in Figure 5 includes an inner wall construction integrally cast but it is to be understood that it may be either in this form or made up of separable units as discussed in connection with Figures 2, 3 and 4.

Thus, it will be seen from the foregoing that there has been provided a simple inexpensive inner wall of durable construction using the minimum material and by the use of which the transmission of moisture and vibration from one wall to the other is minimized by providing a long solid path of travel and with the minimum necessity for additional moisture proof or sound proof material because of the very limited area of contact of the inner wall with the two walls it supports.

60 I claim:

1. For use in a building construction as a spacing and supporting means for two wall structures, an elongated inner wall comprising a body portion with relatively narrow ribs extending in staggered relationship from opposite sides thereof and appreciably longitudinally spaced from each other so that when said inner wall is placed between said wall structures said ribs are substantially in abutment with the adjacent of said wall structures, leaving an appreciable space between the greater majority of the length of the inner wall and both of said wall structures and rendering the solid path of conduction between said wall structures appreciably greater than the actual distance therebetween, said inner wall comprising a plurality of separate units provided with locking elements whereby they may be joined together longitudinally in assembled position.

2. For use in a building construction as a spacing and supporting means between two wall structures, an elongated inner wall comprising a body portion with relatively narrow ribs extending in staggered relationship from opposite sides thereof and appreciably longitudinally spaced from each other so that when said inner wall is placed between said wall structures said ribs are substantially in abutment with the adjacent of said wall structures, leaving an appreciable space between the greater majority of the length of the inner wall and both of said wall structures and rendering the solid path of conduction between said wall structures appreciably greater than the actual distance therebetween, said inner wall comprising a plurality of separate units provided with locking elements whereby they may be joined together longitudinally in assembled position. 5

3. As an element of building construction, an elongated structural supporting member comprising a load sustaining body portion having ribs extending transversely from the opposite sides thereof and substantially the height thereof, said ribs being staggered and longitudinally spaced from each other, said supporting member including a plurality of units with coupling means whereby they may be joined together longitudinally in assembled position the joints thus formed being longitudinally spaced with respect to all of said ribs. 20

4. For use in a building construction as a spacing and supporting means for two wall structures, an elongated inner wall comprising a body portion with relatively narrow ribs extending in staggered relationship from opposite sides thereof and appreciably longitudinally spaced from each other so that when said inner wall is placed between said wall structures said ribs are substantially in abutment with the adjacent of said wall structures, leaving an appreciable space between the greater majority of the length of the inner wall and both of said wall structures and rendering the solid path of conduction between said wall structures appreciably greater than the actual distance therebetween, said body portion having a reinforcing member extending substantially longitudinally thereof and said ribs each having separate reinforcing members extending substantially longitudinally thereof and in a plane substantially at right angles to the reinforcing members of said body portion. 30

5. For use in a building construction as a spacing and supporting means between two wall structures, an elongated inner wall comprising a body portion with relatively narrow ribs extending in staggered relationship from opposite sides thereof and appreciably longitudinally spaced from each other so that when said inner wall is placed between said wall structures said ribs are substantially in abutment with the adjacent of said wall structures, leaving an appreciable space between the greater majority of the length of the inner wall and both of said wall structures and rendering the solid path of conduction between said wall structures appreciably greater than the actual distance therebetween, said inner wall comprising a plurality of separate units provided with locking elements whereby they may be joined together longitudinally in assembled position, said body portion having a reinforcing member extending substantially longitudinally thereof and said ribs each having separate reinforcing members extending substantially longitudinally thereof and in a plane substantially at right angles to the reinforcing members of said body portion. 55

6. For use in a building construction as a spac- 70

ing and supporting means between two wall structures, an elongated inner wall comprising a body portion with relatively narrow ribs extending in staggered relationship from opposite sides thereof and appreciably longitudinally spaced from each other so that when said inner wall is placed between said wall structures said ribs are substantially in abutment with the adjacent of said wall structures, leaving an appreciable space between the greater majority of the length of the inner wall and both of said wall structures and rendering the solid path of conduction between said wall structures appreciably greater than the actual distance therebetween, said inner wall comprising a plurality of separate units provided with locking elements whereby they may be joined together longitudinally in assembled position, the joints thus formed being out of contact with and appreciably spaced from each of said wall structures.

20 7. For use in a building construction as a spacing and supporting means for two wall structures, an elongated inner wall comprising a body portion with relatively narrow ribs extending in staggered relationship from opposite sides thereof and appreciably longitudinally spaced from each other so that when said inner wall is placed between said wall structures said ribs are substantially in abutment with the adjacent of said wall structures, leaving an appreciable space between the greater majority of the length of the inner wall and both of said wall structures and rendering the solid path of conduction between said wall structures appreciably greater than the actual distance therebetween, and heat insulating material substantially filling the space between said inner wall and said wall structures.

25 8. For use in a building construction as a spacing and supporting means for two wall structures, an elongated inner wall comprising a body portion with relatively narrow ribs extending in stag-

gered relationship from opposite sides thereof and appreciably longitudinally spaced from each other so that when said inner wall is placed between said wall structures said ribs are substantially in abutment with the adjacent of said wall structures, leaving an appreciable space between the greater majority of the length of the inner wall and both of said wall structures and rendering the solid path of conduction between said wall structures appreciably greater than the actual distance therebetween, at least one of said ribs having affixed thereto at its outer extremity a strip of material that is inherently impervious to moisture.

9. As an element of building construction, an elongated structural supporting member, comprising a load sustaining body portion having ribs extending transversely from the opposite sides thereof, and substantially the height of the body portion, said ribs being staggered and longitudinally spaced from each other, said supporting member including a plurality of units with coupling means whereby they may be joined together longitudinally in assembled position, the joints thus formed being longitudinally spaced with respect to said ribs and transversely spaced from each of the structures it supports.

10. As an element of building construction, an elongated structural supporting member comprising a load sustaining body portion having a plurality of ribs extending transversely from each of two opposite sides thereof and substantially the height of the body portion, said ribs being staggered and longitudinally spaced from each other, said body portion having a reinforcing member extending continuously substantially throughout the length thereof and each of said ribs having a separate reinforcing member extending substantially throughout its length.
